RIDER-OPERATED POWER-DRIVEN
LAWN-MOWER

Leonard M. Strunk, Coatesville, Pa.

Application November 5, 1956, Serial No. 43,658

Term of patent 14 years

(Cl. D40—1)

Figure 1 is a perspective view of a rider-operated power-driven lawn-mower showing my new design;

Figure 2 is a side elevational view thereof;

Figure 3 is a front elevational view thereof;

Figure 4 is a top plan view thereof; and

Figure 5 is a rear elevational view thereof.

I claim:

The ornamental design for a rider-operated power-driven lawn-mower, as shown.
